DESIGN FOR A CORNER ELEMENT FOR HARDBOARD BOX

Herbert C. Dee, Kenilworth, Ill.

Application April 28, 1944, Serial No. 113,396

Term of patent 14 years

(Cl. D58—12)

To all whom it may concern:

Be it known that I, Herbert C. Dee, a citizen of the United States, residing at Kenilworth, in the county of Cook and State of Illinois, have invented a new, original, and ornamental Design for Corner Element for Hardboard Box, of which the following is a specification, reference being had to the accompanying drawing, forming part thereof.

Figure 1 is a perspective view of a corner element for a hardboard box, showing my new design;

Figure 2 is a perspective view of a corner element as seen from the back side;

Figure 3 is a side view of the corner element incorporating my new design;

Figure 4 is a top plan view of a corner element shown in Figure 1; and

Figure 5 is a bottom plan view of the corner element shown in Figure 1.

I claim:

The ornamental design for a corner element for hardboard box, as shown.

HERBERT C. DEE.
